UNITED STATES PATENT OFFICE.

CLINTON C. MURPHY, OF CHICAGO, ILLINOIS, ASSIGNOR TO P. H. MURPHY COMPANY,
OF PARNASSUS, PENNSYLVANIA, A CORPORATION OF PENNSYLVANIA.

RUNNING-BOARD SADDLE.

1,145,207.

Specification of Letters Patent.

Patented July 6, 1915.

Application filed February 9, 1914. Serial No. 817,517.

To all whom it may concern:

Be it known that I, CLINTON C. MURPHY, a citizen of the United States, and a resident of the city of Chicago, in the county of Cook and State of Illinois, have invented a new and useful Improvement in Running-Board Saddles, of which the following is a specification.

My invention relates to running board 10 saddles, particularly to that type which is adapted for use with car roofs formed of metal roof sheets joined together by up-standing seams.

The principal object of my invention is 15 to provide a metal running board saddle which will not injure the roof sheets or their seams, and which will aid in preventing leakage through the roof.

A further object is to attain certain other 20 advantages as will be more fully set forth hereinafter.

The invention consists in the parts, and in the arrangements and combinations of parts as will more fully appear hereinafter.

25 In the accompanying drawings, which form part of the specification, and in which like reference characters refer to like parts throughout the several views, Figure 1 is a top plan view of a running board saddle 30 embodying the invention; Fig. 2 is a vertical transverse section on the line 2—2 on Fig. 1; Fig. 3 is an end elevation; Fig. 4 is a side elevation; Fig. 5 is a vertical longitudinal section on the line 5—5 on Fig. 1.

35 For the purpose of illustration, the running board saddle embodying the invention has been shown as applied to an outside metal car roof formed of roof sheets 1, joined to one another by arched seams 2 40 extending transversely of the car and arched seams 3 extending longitudinally of the car above the ridge pole 4. The roof sheets 1 rest upon a wooden sheathing 5 supported on carlines and the ridge pole 4 according 45 to the usual construction.

The body of the running board saddle is made of metal and is preferably stamped and bent from sheet metal. The running boards 6 are supported upon spaced seats 50 7 formed by horizontal flanges upon the spaced upright members 8. The flanges forming the seats 7 extend in opposite directions from the upright members 8. In each of the seats 7 is a row of circular holes 55 9, and through these holes 9 are passed bolts

10 which extend through the running boards 6 and hold them firmly in position. Between the upright members 8 the body of the saddle is formed with an inverted channel or ridge 11. The sides of the inverted 60 channel 11 are spaced from the upright members 8, leaving spaced feet 12, one on each side of said inverted channel. The body of the saddle between the seats 7 is bent to conform to the pitch of the roof. 65

Disposed within the inverted channel 11 is an insert 13 of wood, pressed fiber, or other suitable non-abrasive material, which is shaped to fit in the inverted channel 11, and to have portions extending under the 70 feet 12. The insert 13 has a groove 14 in its under face extending longitudinally thereof, which overlies the seam 2 and has its walls spaced therefrom. The insert 13 has a groove 15 in its under face extending 75 transversely thereof to accommodate a corner cap 16 which is ordinarily used with this type of roof. The feet 12 are also bent to form arches 17 to accommodate the corner cap 16. The under face of the insert 80 13 rests upon the roof sheets 1. A bolt 18 passes through the ridge pole 4, a boss 19 on the corner cap 16 and through the inverted channel 11. The bolt 18 holds the saddle in position, but does not press the insert 13 against the roof sheets 1 so as to bind 85 them against movement. The boss 19 of the corner cap 16 is embedded in the insert 13.

By this construction, it is possible to use 90 the same metal body of the saddle in connection with roofs having different sizes of seams by interchanging inserts 13 having the sizes of the grooves in their under faces corresponding to the sizes of the different 95 seams. When the car is in service, there is a slight relative movement of the roof sheets and the running board saddle, and if the metal body of the saddle were in contact with the roof sheets, the rubbing action of 100 the saddle upon the roof sheets would wear off the protecting coating on the roof sheets and permit them to rust. In this construction, no part of the metal body of the saddle touches the roof sheets, and all of the 105 rubbing action takes place between the non-abrasive insert 13 and the roof sheets, so that the roof sheets are not worn or injured. The insert 13, being formed of wood, pressed fiber, or some similar material, is resilient 110

and will not tear or break the seams between the roof sheets, when the weight upon the running boards and the racking of the car in service cause the saddle to shift. The 5 boss 19 of the corner cap 16 may be pressed into the insert 13 so as to prevent leakage around the bolt 18. The resiliency of the insert 13 serves to hold the nut tight upon the bolt 18 and prevent it from working 10 loose under the varying stresses which are applied to it.

It is to be understood that the particular form of running board saddle which I have shown and described may be considerably 15 modified without departing from my invention. I do not wish, therefore, to be limited to the exact construction which I have shown and described.

What I claim is:

- 20 1. A running board saddle comprising a metal body adapted to support running boards, and a piece of non-abrasive material attached thereto and projecting below the under face of said body in position to bear 25 on the roof and serve as a rubbing member.
2. A running board saddle comprising a metal body adapted to support running boards, and a piece of non-abrasive material attached to the under face of said body, 30 said piece having grooves in its under face adapted to straddle the seams between the roof sheets of a car roof.
3. A running board saddle comprising a metal body having spaced seats adapted 35 to support running boards and provided

with an inverted channel in its under face, and a wooden insert fitting in said inverted channel, said insert having a longitudinal and a transverse groove in its under face.

4. A running board saddle comprising a 40 metal body adapted to support running boards, and having an inverted channel in its under face, and an insert of non-abrasive material fitted in said inverted channel, said insert having a longitudinal groove in its 45 under face.

5. A running board saddle comprising an integral body of sheet metal, bent to form horizontal spaced seats adapted to support running boards, and having an inverted 50 channel in its under face, and a wooden insert fitting in said inverted channel and having grooves in its under face adapted to straddle the seams of a metal car roof.

6. A running board saddle comprising a 55 metal body having spaced seats adapted to support running boards, and a piece of non-abrasive material attached to the under face of said body, said piece having a longitudinal groove in its under face. 60

7. A running-board saddle formed of a casting provided with a recessed bottom and a supporting pad of non-abrasive material fitting said recess.

Signed at Chicago, Cook county, Illinois, 65
this 4th day of February, 1914.

CLINTON C. MURPHY.
